UNITED STATES PATENT OFFICE.

WALTER AUDAER WILSON, OF ARMLEY, LEEDS, ENGLAND.

GAS-FIRE.

1,156,735.

Specification of Letters Patent. Patented Oct. 12, 1915.

Application filed July 7, 1915. Serial No. 38,570.

To all whom it may concern:

Be it known that I, WALTER AUDAER WILSON, a subject of the King of Great Britain and Ireland, residing at Carlton Works, 5 Armley, Leeds, in the county of York, England, have invented new and useful Improvements in or Connected with Gas-Fires, of which the following is a specification.

This invention relates to improvements in 10 gas fires, having for its objects among others to construct a gas fire adapted to stand on a hearth and to fit into fireplaces or well grates, and to occupy the same position as an ordinary coal fire, and to have a similar 15 contour and appearance, the gas fire being designed to have a high radiant efficiency.

In the first place I made a number of experiments to discover the lowest curve which a preferably well aerated flame would take 20 when burning in proximity to a solid body; having obtained this curve applying the known attractive property a solid has for a flame in its vicinity, I next determined the increased effect of a tubular construction of 25 a "radiator" or so-called fuel placed around the flames. In this manner I arrived at the lowest and longest curve at which to construct the fire to enable a flame to be directed at a curve from, first a vertical direction or 30 nearly so, leading to the horizontal or nearly so; and to efficiently heat up a suitable radiant or so-called fuel to its highest efficiency.

I am aware that it has been previously 35 proposed to construct low fires to resemble coal fires by placing so-called fuel at an angle over a flame and forcing such flame by baffles or obstructions to take an inclined course with a result that heat and products 40 of combustion escaped and there was a consequent loss of efficiency. In my device the flame is entirely unobstructed, being directed in its desired course by the attractive 45 quality of a back or solid arranged in proximity to the flame. The curve of the flame is in one direction and unbaffled.

The invention is clearly illustrated in the 50 accompanying drawing, which, with the letters of reference marked thereon, forms a part of this specification, and in which—

Figure 1 is a perspective view of a gas fire constructed in accordance with my invention. Fig. 2 is an enlarged vertical section through the same from front to rear.

55 Like letters of reference indicate like parts in the different views.

In the disclosed form of my invention, having obtained the desired angle (which may vary slightly) at which to place the back B, and to which the flame will be attracted, I surround the flame or flames with a series of fire clay or like tubular radiants R having open-work fronts, such as R², said radiants being formed to the desired curve. The backs R' of the radiants may be imperforate or substantially so. The shape of the radiants is first in the initial direction of the flame and then gradually curving backward, becoming more horizontally inclined toward the top, as shown, that is leaving a gradually tapered passage between the back and the front. The back or support B is placed behind the radiants to prevent loss of heat behind the fire, and such back is kept at a distance away from the radiants by projections or the like P formed on the back, providing a space P' behind the back R' to prevent loss of heat by conduction. If desired, in order to more closely imitate the appearance of a coal fire, the outer surface 80 of the solid portions of the open-fronted radiants may be colored or blackened. In constructing the radiants any number may be formed together, and there may be two or more sets, such as upper or lower ones, as shown in Fig. 2, joined together by suitable joint, as shown at R³. The pattern of the open fronts may be arranged to appear continuous, after a manner set forth in the 85 British Patent No. 16571 of 1913.

It is to be noted that the radiants are disposed in relation to the flames in such a manner that they in no way impede or check the flame and so do not interfere with the sufficient or complete combustion, and that correctly constructed radiants prevent escape of flame through the open-work fronts and the said radiants become heated internally throughout their length. It will also be seen that only curved radiants are arranged in connection with an imperforate support and the use of additional cobbles or granules, such as sometimes have been heretofore used over inclined straight tubular pieces of so-called fuel to utilize escaping 95 flames and the products of combustion, are dispensed with.

What is claimed as new is:—

1. A radiant consisting of an open-work front and an imperforate back spaced apart, forming an unobstructed upwardly and rearwardly curved flame shaped first in the 100 105 110

initial direction of the flame and then to a curve to which the unobstructed flame is attracted in a direction from the vertical toward the horizontal.

2. A radiant consisting of an open-work front and an imperforate back spaced apart, forming an unobstructed upwardly and rearwardly curved flue shaped first in the initial direction of the flame and then to a curve to which the unobstructed flame is attracted in a direction from the vertical toward the horizontal, said flue tapering from its lower to its upper end.

3. A gas fire, designed to resemble a coal fire, comprising an upwardly and rearwardly

curved radiant consisting of an open-work front and an imperforate back spaced apart, forming an unobstructed flue shaped first in the initial direction of the flame and then to a curve to which the unobstructed flame is attracted in a direction from the vertical toward the horizontal, and a back support spaced from said radiant.

In testimony whereof I have signed my name to this specification in the presence of 25 two subscribing witnesses.

WALTER AUDAER WILSON.
